LOOM HEDDLE AND METHOD OF MAKING
THE SAMEJohn Jacob Kaufmann, Elkins Park, Pa., assignor
to Steel Heddle Manufacturing Company, Phil-
adelphiea, Pa., a corporation of Pennsylvania

Application July 24, 1934, Serial No. 736,650

12 Claims. (Cl. 139—94)

My invention relates to loom heddles and methods of making the same, and relates more particularly to heddles used for weaving heavy fabrics such as duck, although it should of course be understood that a heddle made in accordance with my present invention, and in the manner hereinafter set forth, may, if desired, be used for other types of weaving.

Heretofore, in the weaving of heavy fabrics such as duck, the weight of the harness used for manipulating the warp thereof has been quite objectionable.

When such heddles are made of a continuous strip of material, it is necessary, in order to reduce the weight, to shear or cut out the side portions of the strip between the warp eye and the eyes provided for mounting the heddle on the supporting rods. This is an expensive and difficult operation, and of course entails a considerable waste of the material from which the heddles are formed.

In other types, the heddles have been made of round wire throughout, but when so made difficulty has been experienced in attempts to obtain satisfactory forms of warp eyes.

Various attempts have also been made to construct heddles of composite parts soldered or otherwise secured to each other, but the soldering of the various parts is a difficult and relatively expensive operation, and the heddles made in this manner would frequently come apart, when in use, at the places where they were soldered, as it is not possible to determine the weakness of the joints upon a mere inspection.

The principal object of the present invention is to provide a heddle of the composite type which may be readily and expeditiously made and assembled, which will be so constructed and arranged that the parts will be securely held together without dependence being placed upon solder or the like for the securing means.

A further object of my invention is to provide a heddle of the character aforesaid having the requisite strength, in which the warp eye may be properly shaped for ease of manipulation and for resistance to the wear occasioned by the constant passing of the warp therethrough.

A further object of my invention is to provide a heddle of the character aforesaid, which may be economically produced.

The nature and characteristic features of my invention will be more readily understood from the following description, taken in connection with the accompanying drawing forming part hereof, in which:

Figure 1 is an elevational view of a preferred form of heddle embodying the main features of my present invention and made according to the method thereof, the face shown being that looking transversely to the longitudinal extension of the warp;

Fig. 2 is an edge elevation thereof;

Fig. 3 is a view similar to Fig. 1, illustrating a modified form of heddle;

Figs. 4, 5, and 6 are elevational views illustrating successive steps in the uniting of the warp eye member to the portions of the heddle which extend therefrom;

Fig. 7 is a face view, enlarged, of one of the warp eye members, detached;

15

Fig. 8 is a side elevation thereof;

Fig. 9 is an enlarged detail view, in front elevation, of one end of the wire to be attached to the warp eye member;

Fig. 10 is a side elevation thereof;

20

Fig. 11 is a transverse section, taken on the line 11—11 of Fig. 10, still further enlarged; and

Fig. 12 is a transverse section taken on the line 12—12 of Fig. 2, also greatly enlarged.

It will, of course, be understood that the description and drawing herein contained are illustrative merely, and that various modifications and changes may be made in the structure disclosed without departing from the spirit of the invention.

Referring to the drawing, in the particular embodiment of my invention therein shown, the warp eye member 15 is preferably punched and formed from a flat strip or sheet of metal, this member being of approximately elliptical outline, 35 and having a central eye 16 for the passage of the warp.

Each end of the warp eye members 15 is provided with a slot 17, in which the end of a wire 18, forming the adjacent portion of the heddle, 40 is positioned and held, as hereinafter more fully set forth. Each slot 17 is preferably of a peculiar dovetail shape, the side margins of said slot being parallel for a portion of their length, adjacent the outer end, and the inner end of 45 said slot being widened to form the dovetail hereinbefore referred to.

The side portions 19 of the warp eye member 15, adjacent the central warp eye 16, are preferably bent out of the main plane of the eye 50 member 15, as shown in Fig. 8 of the drawing, although this is not essential, and if desired the warp eye member 15 may be left flat throughout.

The ends of the wires 18 which are to engage the warp eye member 15 are shaped as shown in 55

Figs. 9, 10, and 11 of the drawing, so as to provide a portion indented on both sides, as at 20, to a thickness corresponding to the width of the slot 17 where the margins thereof are parallel. In 5 the ends of the wires 18, on each side of the indentations 20, there are provided ridges 21, which extend out over the faces of the warp eye member 15 when the indented portion 20 of the end of the wire is inserted in the slot 17 of said warp 10 eye member.

In making the heddle, after the parts are shaped as aforesaid (see Figs. 4, 7, 9, and 10), the ends of the wires 18 are brought to engagement with the dovetail slots 17 (see Fig. 5), and 15 the alignment of these two parts will be maintained by the engagement of the parallel side portions of the slot 17 with the indentations 20 of the wires 18.

While the parts are so positioned, pressure is 20 exerted on the end portions of the wires 18 by means of a suitable press, which will cause the metal at the ends of said wires to fill out the dovetailed inner ends of the slots 17, and at the same time cause the overlapping side portions 25 21 of the wires to be spread still further over the respective side faces of the warp eye member 15, adjacent the slots 17, and in intimate contact with said faces. After this operation has been performed, the warp eye member 15 will be 30 securely attached to the ends of the wires 18 (see Fig. 6).

In the form of heddle shown in Figs. 1 and 2 of the drawing, the eyes at the ends of the heddle, for mounting the same on the supporting 35 rods, may be formed by providing members 22 which are punched and formed from flat metal, each having a central slot 23 constituting the eye through which a heddle supporting rod extends when the heddles are mounted in the 40 loom.

Each of the eye members 22 in this form is provided at its inner end with a slot which is similar in conformation to the slots 17, hereinbefore described, which are provided at the ends 45 of the warp eye member 15. The end of the wire 18 is positioned and secured in the slot at the end of the member 22 in the same manner as it is positioned and secured in the slot 17 in the central warp eye member 15, and hence 50 need not be further described in detail.

In the form of heddle shown in Fig. 3 of the drawing, the eyes for mounting the heddles on the supporting rods are formed by integrally continuing the wire 18 and bending the same to 55 form a flat loop 22^a, as shown.

The wire 18, from which the portions of the heddle extending from the warp eye member 15 are formed, is preferably round in cross-section, but it will be noted that, by reason of the method 60 of construction employed, it is not necessary to impart any twist to this wire in order to secure the usual angular relationship of the warp eye member 15 with respect to the portions of the heddle through which the heddle supporting rods 65 extend. Thus any desired angular position of the warp eye member 15 with respect to the eye portions at the ends of the heddle may be readily and accurately obtained, resulting in uniformity of the product. Consequently, the warp 70 eye members 15 in a series of heddles in a frame will nest properly with respect to each other.

After the heddles are constructed as aforesaid, the same are preferably dipped in a solder bath, so that the surfaces of the heddle parts will be 75 given a protective coating (not shown). The

solder thus applied will permeate any interstices which may be left in the formation of the heddles, and will also serve to provide smooth surfaces where the several parts are joined to each other.

A heddle constructed as aforesaid will be relatively light, yet of sufficient strength for its desired purpose, and will be characterized by freedom in the action of the warp when the harness is manipulated to form successive sheds. The 10 warp eye member 15 may be so shaped as to guide the warp ends controlled by adjacent frames past the warp eyes without any objectionable interference.

I claim:

1. A loom heddle having an eye portion, said eye portion comprising a member having an eye and also having a dovetail slot at one end, and a portion adjacent the eye member comprising a single strand of wire, an end portion of the wire 20 extending into and filling said slot.

2. A loom heddle having an eye portion, said eye portion comprising a member having an eye and also having a dovetail slot at one end, and a portion adjacent the eye member comprising a 25 single strand of wire, an end portion of the wire extending into and filling said slot, and a part of said end portion extending over the side faces of the eye member adjacent the slot.

3. A loom heddle having a central warp eye 30 portion and eye portions at the ends thereof for mounting the heddle upon the supporting rods, the warp eye portion comprising a member having a central warp eye and a dovetail slot at each end, each of the end eye portions comprising a 35 member having an eye and a dovetail slot at one end, and portions extending from the warp eye member to the end eye portions each comprising a single strand of wire, each end portion of each wire extending into and filling one of said slots. 40

4. A loom heddle having a central warp eye portion and eye portions at the ends thereof for mounting the heddle upon the supporting rods, the warp eye portion comprising a member having a central warp eye and a dovetail slot at each 45 end, each of the end eye portions comprising a member having an eye and a dovetail slot at one end, and portions extending from the warp eye member to the end eye portions each comprising a single strand of wire, each end portion of each wire 50 extending into and filling one of said slots, and a part of said end portion extending over the side faces of the eye member adjacent the slot.

5. A loom heddle having a central warp eye portion comprising a member having a central 55 warp eye and dovetail slots at the ends, and each of the portions of the heddle adjacent the warp eye member comprising a single strand of wire, an end portion of each wire extending into and filling one of said slots. 60

6. A loom heddle having a central warp eye portion comprising a member having a central warp eye and dovetail slots at the ends, and each of the portions of the heddle adjacent the warp eye member comprising a single strand of wire, 65 an end portion of each wire extending into and filling one of said slots, and a part of said end portion extending over the side faces of the eye member adjacent the slot.

7. A loom heddle having a central warp eye 70 portion comprising a member having a central warp eye and dovetail slots at the ends, and each of the portions of the heddle adjacent the warp eye member comprising a single strand of wire, an end portion of each wire extending into and 75

filling one of said slots, and a part of said end portion extending over and in intimate contact with the side faces of the eye member adjacent the slot.

5. A loom heddle having eye portions at the ends thereof for mounting the heddle upon the supporting rods, each of said end eye portions comprising a member having an eye and a dovetail slot at one end, and each of the portions of the heddle adjacent the end eye portion comprising a single strand of wire, an end portion of each wire extending into and filling said slot.

10. 9. In the manufacture of loom heddles, the method which consists in forming an eye member with a dovetail slot, then inserting an end portion of a wire in the slot of the eye member, and thereafter deforming the inserted end of the wire to cause the metal thereof to fill the slot.

15. 10. In the manufacture of loom heddles, the method which consists in forming an eye member with a dovetail slot, shaping the end of a wire to provide a reduced portion thereof of a thickness corresponding to the width of the narrow portion of the slot in the eye member, then inserting the shaped end portion of the wire 20 in the slot of the eye member, and thereafter deforming the inserted end of the wire to cause the metal thereof to fill the slot and to cause por-

tions of the wire to be spread over and forced into intimate contact with the side faces of the eye member adjacent the slot.

11. In the manufacture of loom heddles, the method which consists in forming a warp eye member with a central warp eye and a dovetail slot at each end, then inserting end portions of wires in the slots of the eye member, and thereafter deforming the inserted end of each wire to cause the metal thereof to fill the slot in which it 10 is inserted.

12. In the manufacture of loom heddles, the method which consists in forming a warp eye member with a central warp eye and a dovetail slot at each end, shaping the ends of wires to 15 provide at an end of each wire a portion thereof of a thickness corresponding to the width of the narrow portions of the slots in the eye member, then inserting the shaped end portions of the wires in the slots of the eye member, and thereafter deforming the inserted end of each wire to cause the metal thereof to fill the slot in which it 20 is inserted and to cause portions of the wire to be spread over and forced into intimate contact with the side faces of the eye member adjacent said 25 slot.

JOHN JACOB KAUFMANN.
